UNITED STATES PATENT OFFICE.

HENRY MERZ, OF POLLASKY, CALIFORNIA.

PLANE.

SPECIFICATION forming part of Letters Patent No. 511,349, dated December 26, 1893.

Application filed May 1, 1893. Serial No. 472,568. (No model.)

To all whom it may concern:

Be it known that I, HENRY MERZ, of Pol-
lasky, in the State of California, have invented
certain new and useful Improvements in
5 Planes; and I do hereby declare the follow-
ing to be a full, clear, and exact description
of the invention, such as will enable others
skilled in the art to which it appertains to
make and use the same.

10 This invention relates to planes for carpen-
ters and the like, and has for its object to im-
prove devices of a similar character which
have been heretofore employed.

The invention consists of the detail con-
15 struction, combination and arrangement of
parts, substantially as hereinafter fully set
forth, and particularly pointed out in the
claims.

In the accompanying drawings:—Figure 1
20 is a vertical longitudinal sectional view of my
improved plane. Fig. 2 is a view of the cut-
ting blade detached. Fig. 3 is a perspective
view of the cap-plate, screw and adjuncts.
Fig. 4 is a detail perspective view of a part of
25 the adjusting mechanism. Fig. 5 is a bottom
plan view of the cap plate and adjustments
in connection therewith. Fig. 6 is a rear end
elevation of the clamp and cap plate.

Referring to the drawings, A designates the
30 main or body portion of the plane, having the
ordinary opening a which terminates in the
transverse slot a' through which the cutting
blade B projects. In this cutting blade is a
T-shaped opening, in the outer end of which
35 is a lug b forming a pivot point. In the rear
inclined wall of opening a is set a metallic
plate b' into a threaded opening in which is
screwed a screw C, the head d of which has
an overhanging lower flange d'.

40 D is a cap plate having a longitudinal slot
d², and a rear central cut away portion d³,
and two corresponding sockets d⁴ on either
side of said cut-away portion. To the under
45 side of this cap-plate is fastened a spring-
plate E from which extend parallel arms e
free at their outer ends.

F is a clamp which fits between sockets d⁴
and is pivoted by a rod f supported by said
50 sockets. This clamp is rounded at its pivoted
end and is provided with two curved cam-lugs
f', which when the clamp is lowered will ex-
tend through the cut-away portion of the cap-

plate and bear upon the free ends of the
spring-arms, causing the latter to bind against
the upper surfaces of the cutting blade.

55 G is a block having upper shoulders g, and
a threaded projection g' which is extended
up through slot d² of cap-plate D and upon it
is screwed a nut g² designed to bind against
a washer g³ extending across said slot. The
60 shoulders g are drawn against the lower walls
of slot d², said walls being made tapering.
The lower end of block G has an acute lip g⁴
extending therefrom and designed to engage
with the overhanging portion of the headed
65 screw C. The lip is formed into somewhat of
a point at about its center so as to securely
engage the head of the screw and be held sta-
tionary. Through a threaded opening in this
70 block extends a screw rod H, which fits in the
T-shaped opening of the cutting blade. A
socket in the outer end of this screw-rod re-
ceives the lug b. Adjacent to this end is a
milled head h by which the screw rod is read-
ily and easily turned.

75 The operation of my improved plane is
readily understood from what has gone before.
To quickly effect the adjustment of the cut-
ting blade the operator raises the clamp so as
to release the frictional engagement between
80 the cutting blade and cap-plate, permitting
the spring arm to be free. By turning the
screw rod the cutting blade can be moved in
either direction, the block secured to said cap-
plate being stationary by reason of the en-
85 gagement with the screw C. After the cut-
ting blade has been adjusted the operator
closes down the clamp and the cam-lugs there-
of bind the spring arms down on said cutting
blade, making a firm frictional contact there-
90 with and holding the cutting blade in posi-
tion. By turning the screw-rod the cutting
blade can still be further adjusted but is
firmly held at any desired point, the cap-
plate being stationary by reason of the en-
95 gagement of the acute lip of the block with
the head of the screw C.

The advantages of my invention are ap-
parent to those skilled in the art to which it
appertains, and it will be specially observed
100 that the mechanism employed is simple and
not liable to readily get out of order.

I claim as my invention—

1. The herein described plane, comprising

a body with a slot or opening therein, a headed stud or screw C arranged obliquely and having a flanged head, a blade having a longitudinally disposed slot with a pivot at the 5 central upper portion of the same, a cap plate with a slot therein in which is adjustably mounted a block formed with a shouldered groove engaging said flanged head of the stud or screw, and having a screw threaded opening extended transversely therethrough, a spring clamp having its upper end pivotally connected to the upper portion of the said cap plate, and a screw rod located in the said longitudinally disposed slot of the blade, and 10 having a milled nut thereon whose upper end engages the pivot at the upper end of said slot in the blade, said nut being located in the slot, substantially as described.

2. The herein described plane comprising 20 a body having a stud or screw therein with a flanged head, a blade having a longitudinally disposed slot with a pivot at the upper terminating wall of the same, a cap plate provided with a slot and having sockets at the upper 25 portions of the same with a central cutaway

part, a block adjustably mounted in the slot of the cap plate, and formed with a lower shouldered groove to engage the flanged head of the said stud or screw, a spring clamp mounted on the cap plate and having its upper end pivotally located in the cut-away part of the latter, and pivoted to the sockets thereof, having parallel arms e, which are free and bear against the blade to produce a spring action and a screw rod H mounted in the longitudinally disposed slot of the blade and extending through the aforesaid block, said screw rod having a milled nut on the upper end thereof for adjusting the blade and having its upper surface rotatably engaging the 30 said pivot, said nut being revoluble in the slot of the blade, substantially as described.

In testimony whereof I have signed this specification in the presence of two subscribing witnesses.

HENRY MERZ.
